UNITED STATES PATENT OFFICE.

JOSEPH M. PREGENZER, OF CHICAGO, ILLINOIS.

X-RAY TUBE.

1,253,721.

Specification of Letters Patent. Patented Jan. 15, 1918.

Application filed January 5, 1916. Serial No. 70,370.

To all whom it may concern:

Be it known that I, JOSEPH M. PREGENZER, a citizen of the United States of America, and a resident of Chicago, county of Cook, 5 and State of Illinois, have invented certain new and useful Improvements in X-Ray Tubes, of which the following is a specification.

This invention relates to Roentgen ray 10 generators or X-ray tubes, and especially to that part of the tube or neck which is adjacent to the cathode, which part heretofore has been subject to a serious tendency to break down under the action of the heat generated at the cathode:

The main objects of this invention are to provide improved means for increasing the durability of X-ray tubes; to provide improved means for protecting the glass wall 20 of the tube adjacent to the cathode from the heat there generated; to provide a durable heat-proof jacket or shield between the neck wall and the cathode, and surrounding the latter, whereby the glass wall may be 25 screened from the direct rays of heat from the cathode; and to provide a jacket so formed and arranged as to furnish a circulation gap or space on both sides whereby the rarefied gases in the tube may circulate 30 through the neck past the cathode on the inside and outside of the jacket, preferably in opposite directions respectively, and so temper the heat near the cathode and prevent injury to the adjacent wall of the tube.

35 An illustrative embodiment of this invention is shown in the accompanying drawings, in which—

Figure 1 is a perspective view of an X-ray tube embodying this invention.

40 Fig. 2 is an enlarged vertical axial section through the cathode and jacket and adjacent members, parts of which are shown fragmentarily.

In the construction shown in the drawings, the shape and general appearance of 45 the bulb or tube 1 is substantially like that of tubes used heretofore, except for the jacket or shield 2 and the mounting means therefor in the lower part of the tube. The 50 anode 3 is electrically connected to the positive terminal 4 which is supported by the tubular projection 5. The cathode 6 is mounted on the terminal rod 7 disposed in the tubular extension 8 whereby the current leaves 55 the tube. The anti-cathode 9 is mounted on the inner end of a massive bar 10 held in the

tubular projection 12, said bar 10 also being connected to the positive side of the source of current, and constituting an additional anode. The members 3 and 10 are 60 electrically connected by the means 15 attached to the terminals 4 and 16. The vacuum regulator 17 disposed on one side of the tube does not constitute any part of the present invention. The same is true of 65 the anode and anti-cathode members.

The cathode 6 is concave on its upwardly facing active side and is formed and disposed in such manner as to focus the cathode rays emanating therefrom on the 70 anti-cathode plate 9 which is the source or origin of the X-rays. Said plate 9 is disposed at an angle for directing the X-rays laterally as customary in X-ray tubes. Said cathode is somewhat saucer-shaped and is attached demountably on the inner or upper 75 end of the terminal rod 7. Said rod except adjacent to its upper end is inclosed in a tubular glass covering 19, which projects inward from the lower end or bottom of said 80 extension 8 of the X-ray tube, said rod 7 being sealed in the glass, as will be understood. The circular edge of the flaring sides of the cathode is disposed at or near the neck of the tube, nearly opposite the point 20 where the 85 downward projection 8 meets the main body of the X-ray tube, said edge being comparatively near the glass wall of the tube.

The shield member or heat screen 2 is cup-shaped and is disposed concentrically about 90 the cathode 6, being spaced somewhat therefrom. The bottom of said shield 2 is formed with a downwardly extending cylindrical part or contracted tubular stem 22 fitting closely upon the rod 7. The lower extremity 95 of said stem is enlarged somewhat at 23 so as to receive and fit tightly upon the upper end of the tubular casing 19 which surrounds and supports the rod 7. The upper end of the rod 7 is screwed into the cathode 100 member 6 at 25 so that the latter may be removed readily for placing the shield 2 on said bar. Said shield is perforated in its lower part, one or more apertures 28 being provided, to permit circulation of the gases 105 as indicated by the arrows on Fig. 2, said shield thus serving as a jacket for directing the circulation. The intense heat generated at the cathode 6 tends to cause the rarefied gases in the cup 2 to rise within the cup, 110 whereupon there is a tendency for circulation of the gases downward adjacent to the

walls of the tube on the opposite side of the cup wall. The jacket 2 thus serves in two ways to protect the walls of the tube adjacent to the cathode, first by screening 5 the wall from the direct rays of heat from the cathode, and second by promoting a circulation of whatever gases there may be in the tube so as to produce a cooling effect on the walls of the tube opposite the cathode. 10 This removal of heat by gaseous convection is assisted by conduction in the shield which carries some of the heat downward to the rod 7 and glass support 19.

The shield or jacket 2 may be of any 15 durable material adapted to withstand the heat, but is preferably made of metal, steel being found preferable, being durable and adapted for ready manufacture at a low cost, and being free from oxidization in the 20 vacuous chamber of the X-ray tube. Metal has a further advantage, for the reason that, being a good conductor of heat, it assists most effectively by conduction to remove the excess of heat from the zone surrounding 25 the edges of the cathode.

The anode and cathode members are preferably made of aluminum, which is light and combines both commercial and practical efficiency. The anti-cathode plate which 30 must be refractory to withstand the intense heat generated by the focused cathode rays, is preferably made of platinum.

Although but one specific embodiment of 35 this invention is herein shown and described, it will be understood that numerous details of the construction shown may be altered or

omitted without departing from the spirit of this invention as defined by the following claims.

I claim:

1. In an X-ray tube, a shield disposed between the cathode and the wall of the tube, said shield being cup-shaped with its walls disposed medially between the cathode and the wall of the tube in spaced relation thereto respectively, and the lower part of said shield being apertured to permit circulation of gas through said shield acting as a jacket. 40

2. An X-ray tube having a main body part and a tubular projecting part, a cathode disposed at the juncture of said body part and projecting part, and a shield disposed between said cathode and the adjacent part of said tube in spaced relation to each, and downwardly extending heat conducting means supporting said shield. 45

3. A metal jacketed cathode comprising the cathode and a supporting stem therefor, a metal jacket open at the top surrounding said cathode in spaced relation thereto, said jacket being open more or less at the bottom and having a contracted tubular stem disposed downwardly and embracing said supporting stem. 50

4. The combination with the cathode neck 65 of an X-ray tube, a cathode, a tubular support in said neck, a metallic shield surrounding said cathode and supported by said tubular support.

Signed at Chicago this 3d day of January, 70
1916.

JOSEPH M. PREGENZER.
